UNITED STATES PATENT OFFICE

GIDEON SUNDBACK, OF MEADVILLE, PENNSYLVANIA, ASSIGNOR TO HOOKLESS FASTENER COMPANY, OF MEADVILLE, PENNSYLVANIA, A CORPORATION OF PENNSYLVANIA

SEPARABLE FASTENER

Application filed March 16, 1927, Serial No. 175,664. Renewed May 17, 1930.

This invention relates to separable interlocking fasteners and has for its object to provide improved means for separating fastener stringers at both ends, and for facilitating reengagement with the interlocking members in their proper relative positions.

According to a feature of the invention the fastener is so arranged that when the slider reaches the lower limit of its travel, 10 disengaging the interlocking members, the stringer carrying one series of interlocking members may be instantly released from contact with the rest of the fastener. The detachable stringer carries a connecting member 15 which passes through the slider and is arranged in a novel manner to cooperate with a connecting member mounted on the other stringer in such a way that when the stringers are brought together again the slider will 20 draw the interlocking members into engagement in the proper order.

The invention will be described in connection with the accompanying drawings in which similar reference characters designate corresponding parts in the several views, 25 and in which

Fig. 1 is a plan view of a separable fastener illustrating one form of the invention;

Fig. 2 is a view similar to Fig. 1, showing 30 the fastener in position to be opened or closed; and

Figs. 3, 4 and 5 are isometric views showing details of the separable connecting members.

In Figs. 1 and 2, flexible stringers 10 and 35 11 are provided with the usual corded edges carrying interlocking members 12 arranged in staggered relation. The slider 13 having diverging channels is movable up and down along the stringers by means of any suitable 40 pull member (not shown) to close or release the opposed interlocking members.

A feature of the invention resides in a connecting member comprising oppositely disposed arms 14 and 15 which are pivotally 45 connected at their lower extremities by means of a yoke 16 and rivet 17. The pivoted arm 14, shown in Fig. 3, is provided with clamping jaws 18 for clamping the corded edge 50 of the stringer 10, and an extended portion 19 which reaches to a point adjacent the

lowermost interlocking member on the stringer.

The pivoted arm 15, shown in Fig. 4, is provided with a bar 20 which connects the two side walls of the arm, and may be formed 55 integral therewith. The inner edge of the arm 14 rests between the side walls of the arm 15 when the connecting member is in the closed position shown in Fig. 1.

A connecting member 21, mounted adjacent 60 the lowermost interlocking member on the stringer 11, includes clamping jaws 22 for receiving and holding the lower end of the corded edge of the stringer 11, as shown in Fig. 2, and a hook 23 which is adapted to 65 engage the bar 20 of the pivoted arm 15. The construction of member 21 is shown in detail in Fig. 5. The long flat face of the member 21 may be fastened adhesively or in any other suitable manner to the stringer 11. 70

The tape 11 is formed with a corded edge 11a as usual in fastener stringers. At its lower end the corded edge is doubled over at 11b and is held in the U-shaped socket 21a of member 21 by a tongue or partition 21b.

When the hook 23 is in engagement with the bar 20 and the slider 13 is in the position shown in Fig. 1, the member 21 rests in the space provided by the extended portion 80 19 of the pivoted arm 14. In this position the lowermost interlocking member on the stringer 10 rests in the cut-away portion 34 of the member 21. The guide arm 14 and the member 21 are so mounted on the stringers 10 85 and 11, respectively, that the initial upward movement of the slider will compel the opposed interlocking members 12 to start into engagement in the proper sequence, shown in Fig. 1, engagement in any other order being 90 impossible. When the fastener is in closed position it will be noted that the square shoulders 21c on the member 21 engage the adjacent square corner on the member 15 to prevent any substantial outward pivotal movement of these parts. In the absence of some such means, the hook member 21 and the arm 15 would pivot on one another and allow the fastener to be opened up when placed under 95 strain at this point.

When the slider reaches the lower limit of its travel, disengaging the opposed interlocking elements as shown in Fig. 2, the hook 23 may be instantaneously freed from the bar 20 and the stringer 11 thus released from contact with the rest of the fastener. However, since the diverging channels of the slider 13 slide onto the pivoted arms 14 and 15, allowing the ends of these arms to protrude through the slider channels, the slider remains on the stringer 10. When it is again desired to close the fastener the hook 23 is slipped over the bar 20 which protrudes through one channel of the slider, and as the slider is raised the opposed interlocking members 12 are drawn together in the proper order. During the upward movement of the slider the connecting members may be kept straight by exerting a downward pull on the ring 24 which is attached to the yoke 16.

It will be obvious that the invention is not to be restricted to the precise construction herein shown and described. Many of the details, such as the structure of the stringers, interlocking members and slider will necessarily vary according to the particular uses for which the fastener is designed. The construction of the cooperating connecting members may also vary widely within the scope of the appended claims.

The invention claimed is:

1. A separable fastener comprising a pair of stringers having opposed series of interlocking members, and a pair of oppositely disposed arms pivoted to each other, one of said arms being permanently connected to one stringer and the other of said arms being detachably connected to the other stringer to permit said stringers to be separated.

2. A separable fastener comprising a pair of stringers having opposed series of interlocking members on their adjacent edges, a pair of arms pivoted to each other, means permanently connecting one of said arms to an end of one stringer, means detachably connecting the other arm to an end of the other stringer, and means for closing said arms to draw the ends of said stringers together.

3. A separable fastener comprising a pair of stringers having opposed series of interlocking members, a slider having diverging channels movable along said stringers to engage and disengage said members, and a pair of arms pivoted to each other, one of said arms being attached to one stringer and the other of said arms being detachably connected to the other stringer to enter said channels to limit the movement of said slider.

4. A separable fastener comprising a pair of stringers having opposed series of interlocking members, a slider movable along said stringers to engage and disengage said members, a hook secured to one stringer adjacent the lower end thereof, an arm secured to the other stringer adjacent the lower end

thereof, a second arm having one end pivoted to said first arm, and means adjacent the other end of the second arm engageable with said hook for detachably connecting said stringers.

5. The combination with a separable fastener comprising a pair of stringers having opposed series of interlocking members, of a stop member including a pair of arms pivoted to each other, one of said arms having an end attached to the lower end of one stringer and the other of said arms having a free end detachably connected to the lower end of the other stringer, and a slider having diverging channels movable along said stringers to engage and disengage said interlocking members and to pass over said pivoted arms to permit the detachable stringer to be connected to and disconnected from the free end of said arm.

6. The combination with a separable fastener comprising a pair of stringers having opposed series of interlocking members and a slider having diverging channels movable along said stringers to engage and disengage said members, of a stop member including a pair of arms pivoted to each other one of said arms having an end attached to the lower end of one stringer and the other of said arms having a free end detachably connected to the lower end of the other stringer, said arms being long enough to protrude through the channels of said slider when the slider reaches the lower limit of its travel to permit the detachable stringer to be connected to and disconnected from the free end of said arm.

7. A separable fastener comprising a pair of stringers having opposed series of interlocking members, a slider movable along said stringers to engage and disengage said members, a member including a pair of fulcrumed arms connected to said stringers and adapted when spread apart to limit the travel of said slider and when drawn together to align the opposed series of interlocking members in the proper sequence, a yoke associated with said arms at the fulcrum point, and a pull member on said yoke for drawing said arms together.

8. A separable fastener comprising a pair of stringers having opposed series of interlocking members, a slider movable along said stringers to engage and disengage said members, a member including an arm connected at one end to one of said stringers and a second arm fulcrumed to the other end of said first mentioned arm, and a member on the other stringer adapted to be connected to said second arm to align the opposed series of interlocking members in the proper sequence.

9. A separable fastener comprising a pair of stringers having opposed series of interlocking members, a slider movable along said

- stringers to engage and disengage said members, a member including an arm connected at one end to one of said stringers and a second arm fulcrumed to the other end of said first mentioned arm, and a member on the other stringer freely insertable through said slider and detachably connected to said second arm to align the opposed series of interlocking members in the proper sequence.
10. A separable fastener comprising a pair of stringers having opposed series of interlocking members, a slider movable along said stringers and having diverging channels to engage and disengage said members, a stop member having a pair of oppositely disposed arms pivoted to each other, one of said pivoted arms being fastened to one of said stringers, and means on the other stringer to engage and disengage the other arm of said stop member.
11. A separable fastener comprising a pair of stringers having opposed series of interlocking members, a slider movable along said stringers and having diverging channels to engage and disengage said members, a stop member having diverging arms pivoted to each other, one of said arms being permanently connected to one of said stringers and the other of said arms being long enough to protrude through a channel of said slider when said slider has reached the lower limit of its travel, and means on the second stringer to engage and disengage the free protruding arm of said stop member.
12. A separable fastener comprising a pair of fastener stringers having opposed series of interlocking members, a slider movable along said stringers and having diverging channels to engage and disengage said members, and a combined slider stop and end connection for said stringers including stop means for limiting movement of the slider, an arm attached to one stringer, one end of said arm protruding through the rear end of said slider when the slider is against said stop means, a hook-like member on the other stringer for detachable connection to the protruding end of said arm, said hook member and arm having cooperating means to prevent substantial relative pivotal movement between said member and arm when the fastener is closed.
13. A separable fastener comprising a pair of fastener stringers having opposed series of interlocking members, a slider movable along said stringers and having diverging channels to engage and disengage said members, and a combined slider stop and end connection for said stringers including a pair of oppositely disposed arms pivotally connected together at their extreme lower ends to extend into the diverging channels of the slider, one of said arms being permanently connected to one stringer, and means on the other stringer for detachable connection with the end of the other arm rearwardly of the slider.
14. A separable fastener comprising a pair of fastener stringers having opposed series of interlocking members, a slider movable along said stringers and having diverging channels to engage and disengage said members, and a combined slider stop and end connection for said stringers including stop means for limiting movement of said slider, an arm protruding through the rear end of said slider when the slider is against said stop means, means connecting said arm to one of said stringers, a member on the other of said stringers adapted to be attached or detached from the protruding end of said arm, and means forming a permanent connection between said member and said stringer including a U-shaped socket for receiving and holding a portion of the stringer.
15. A separable fastener comprising a pair of fastener stringers having opposed series of interlocking members, a slider movable along said stringers and having diverging channels to engage and disengage said members, and a combined slider stop and end connection for said stringers including an arm protruding through the rear end of said slider when the slider is against said stop, means connecting said arm to one of said stringers, a member on the other of said stringers adapted to be detachably connected to the protruding end of said arm, means forming a permanent connection between said member and said stringer including a socket in said member for receiving a portion of said stringer, and a tongue integral with said member engaging said portion of the stringer.
